UNITED STATES PATENT OFFICE.

EDWIN O. WHEELER, OF SPRINGFIELD, OHIO, ASSIGNOR TO THE SPRINGFIELD AUTO DEFLECTOR COMPANY, INC., OF SPRINGFIELD, OHIO, A CORPORATION OF OHIO.

ATTACHMENT FOR HEADLIGHTS FOR AUTOMOBILES.

1,161,175.

Specification of Letters Patent.

Patented Nov. 23, 1915.

Application filed June 23, 1915. Serial No. 35,744.

To all whom it may concern:

Be it known that I, EDWIN O. WHEELER, a citizen of the United States, residing at Springfield, in the county of Clark and State of Ohio, have invented certain new and useful Improvements in Attachments for Headlights for Automobiles, of which the following is a specification, reference being had therein to the accompanying drawing.

10 This invention relates to an attachment for head lights for automobiles and the like and more particularly to a device for eliminating the glare which is usually present in a powerful head light.

15 The object of the invention is to provide a device which will eliminate the glare without dimming the light and without materially reducing the projection of the light, so that the head light will still give ample 20 light and will project this light an ample distance for the operation of the machine.

25 To this end it is a further object of the invention to provide a shield or deflector which will be of such a character and will be so arranged as to deflect the light from the lamp against a selected portion of the reflecting surface of the head light.

30 It is also an object of the invention to provide a device of this kind which can be quickly and easily attached to the lamp of a head light and which can be produced and marketed at a low cost.

35 In the accompanying drawings, Figure 1 is a perspective view of my deflector showing the same applied to an electric lamp bulb; Fig. 2 is a rear elevation of the same; and Fig. 3 is a longitudinal sectional view of a head light showing the bulb and deflector in elevation.

40 In these drawings I have illustrated one embodiment of my invention and have shown the same as comprising a shield which is so arranged as to prevent the light from the lamp from reaching one longitudinal 45 side of the reflecting surface of the head light, in the present arrangement, the lower surface, and from reaching any of the rear portion of the reflecting surface of the head light, thus allowing the light to reach only 50 the forward portion of a part of the reflecting surface. The line of division between the front part of the reflecting surface, which is in the path of the light rays, and the rear part of the reflecting surface, 55 which the rays are prevented from reaching,

is so arranged that the light will be projected ahead, but the upwardly inclined rays will be wholly eliminated, thus projecting a shaft of light below the level of the eyes of a person approaching the machine from 60 ahead, either on foot or in another machine, and eliminating all rays which would tend to produce a glare in the eyes of such a person. Preferably, this shield acts to concentrate the rays against the exposed portion of the reflector, thus intensifying the 65 same.

In the present embodiment of the invention I have shown the device in connection with an electric head light comprising the 70 usual reflector, 1, and electric lamp the latter consisting of a bulb 2 and a base 3 adapted to be inserted in a socket at the rear end of the reflector and having pins adapted to enter slots and lock the lamp in the socket 75 in a well known manner. This is standard lamp construction and need not be shown and described in detail. As here shown the shield is formed of metal, preferably nickel-plated, and constitutes a deflector for the 80 light rays, as well as an opaque shield which prevents the rays from reaching certain parts of the reflector. This deflector comprises a cup-shaped portion 5 adapted to receive one side of the bulb of an electric 85 lamp and inasmuch as these bulbs are commonly spherical in shape this cup-like portion of the deflector is shown as substantially semispherical, but it will be understood that its shape may be modified to adapt it to 90 lamps of different kinds. This cup-like portion of the shield may be arranged to inclose any desired longitudinal portion of the bulb but ordinarily it is preferable that it should inclose the lower portion of the bulb so as 95 to prevent the light striking the lower surface of the reflector and I have so illustrated the same in the present drawings. The reflector further comprises a hood-like portion 6 which co-operates with the cup-like portion 5 to inclose the rear portion of the bulb 2. This hood-like portion is shown as comprising substantially the fourth part 100 of a sphere. Its lower edge overlaps the rear portion of the edge of the cup-shaped part 5 and its sides extend forward to a point near the greatest circumference of the bulb 2. The forward edge of this hood-like part of the deflector is, however, cut back, as shown at 7, so that the central por- 105

tion of the hood terminates a slight distance in the rear of the greatest circumference of the bulb. The point at which the hood terminates may be varied to control 5 the light as desired. The rear portions of the two parts of the deflector are connected one to the other, by soldering or otherwise, to support them normally in a fixed relation and are cut away to form an opening 8 10 through which the base 3 of the lamp projects, this opening being provided with lateral extensions 9 to permit the passage of the pins 4 of the base.

By connecting the two parts of the deflector at their rear portions only I enable 15 the two parts to be adjusted relatively one to the other to facilitate the insertion of the lamp. It will be understood, however, that the two parts of the deflector may be formed 20 and connected in any desired manner, the separate formation being here adopted for manufacturing reasons only. When the base of the lamp has been inserted in the opening 8 of the deflector the deflector will 25 be supported by the lamp itself. To maintain it in its proper relation thereto I prefer to provide the deflector at the forward end of the lamp with a lip 10 having an opening 11 to receive the tip of the bulb. 30 Preferably, a washer 12 is interposed between the bulb and the lip to form a snug connection. The opening 11 is here shown as a transversely extending slot to permit 35 of a slight play or relative displacement of the parts without injury to the lamp.

With a shield of this character attached to the lamp of a head light and arranged in the position shown it will be apparent that the light is prevented from reaching 40 any part of the lower portion of the reflector and from reaching any part of the rear portion of the reflector, thus causing the rays to be directed toward the upper forward portion of the reflector, which portion of the reflector will project the rays a 45 long distance in advance of the head light but will so condense the rays as to eliminate the glare.

It will be further apparent that the device 50 is a very simple one to manufacture and that it can be produced and sold at a low cost and can be readily attached to a head light; and that the bulb can be readily removed when burned out and a new one substituted therefor.

While I have shown and described one embodiment of my invention it will be un-

derstood that this has been chosen for the purposes of illustration only, and that I do not desire to be limited to the details of construction shown and described, for obvious modifications will occur to a person skilled in the art.

Having thus fully described my invention, what I claim as new and desire to secure by Letters Patent, is:—

1. A light deflector for the bulb of an electric head light comprising an opaque reflecting shield having a part to inclose the lower half of said bulb, having another 70 part to inclose substantially the upper rear quarter of said bulb, the two parts of said shield being capable of relative movement to permit the bulb to be inserted in the shield.

2. A light deflector for the bulb of an electric head light comprising a shield having a substantially semi-spherical lower part to receive the lower half of the bulb and having a hood-like part to inclose substantially the upper rear quarter of said bulb, said parts of said shield having their adjacent edges overlapping and having their rear portions cut away to form an opening 80 to receive the base of the bulb.

3. A light deflector for the bulb of an electric head light comprising a semi-spherical shield of opaque material and having reflecting qualities adapted to inclose substantially one-half the lower portion of the bulb, an upper hood overlapping said semi-spherical shield and adapted to cover the upper rear quarter of said bulb, said shield and hood having a rear opening adapted to receive the base of the bulb and the said semi-spherical shield having at its forward portion an apertured extended lug adapted to engage the forward portion of said bulb.

4. The combination, with a head light comprising a reflector and a lamp supported within said reflector, of a shield comprising a cup-shaped part extending around the lower half of said lamp, and a hood-like part extending around the upper rear quarter of said lamp, said cup-shaped part and 105 said hood-like part overlapping and adjustable relatively to each other to allow the insertion of said lamp.

In testimony whereof, I affix my signature in presence of two witnesses.

EDWIN O. WHEELER.
